UNITED STATES PATENT OFFICE.

KATHERINE M. KEOWEN, OF NEW YORK, N. Y.

PIANO-PROTECTING PAD.

No. 870,969.

Specification of Letters Patent.

Patented Nov. 12, 1907.

Application filed March 18, 1907. Serial No. 363,090.

To all whom it may concern:

Be it known that I, KATHERINE M. KEOWEN, a citizen of the United States, and a resident of the city of New York, borough of Brooklyn, in the county of 5 Kings and State of New York, have invented a new and Improved Piano-Protecting Pad, of which the following is a full, clear, and exact description.

This invention relates to certain improvements in devices adapted to be used in connection with pianos 10 or other similar instruments to protect the front panel from being accidentally marred or damaged by the shoes of the player; and the object of the invention is to construct a device compact and complete in itself which may be very readily and easily applied or removed and which does not mar or injure in any way the piano on which it is used.

The device is durable in its nature and may be made of any ornamental design to add to the appearance of the instrument. It may be readily applied without necessitating the removal of the front panel, and by means of the metal clips engaged, the thickness or size of this panel is rendered entirely immaterial. By reason of the heavy padding or wadding involved in the construction, a very effective protection is afforded 25 even though the device in itself is very light in weight. No intricate mechanism is required for fastening the pad in place, as the engagement of the pad with the pedals serves to prevent any lateral movement of the former.

30 The invention consists in certain features of construction and combination of parts, all of which will be fully set forth hereinafter and particularly pointed out in the claims.

Reference is to be had to the accompanying drawings forming a part of this specification in which similar characters of reference indicate corresponding parts in all the figures, and in which

Figure 1 is a front elevation of one form of my improved pad as employed in connection with a piano, 40 the latter being shown in dotted lines; Fig. 2 is a central vertical section; and Fig. 3 is a sectional detail showing the method of securing the pad to the front panel of the instrument.

My improved pad is preferably formed of a suitable 45 supporting sheet of cardboard, papier mâché, or other stiff but somewhat resilient material, and to both sides thereof I provide a suitable covering separated therefrom by padding material and adapted to present an ornamental appearance and prevent blows delivered to 50 the front of the pad from injuring in any way the portion of the piano in contact with the back of the pad. In the drawings I have illustrated the supporting pad as comprising a substantially rectangular sheet 10 of a height substantially equal to the distance from the floor 55 to the top of the front panel of the piano and of a length substantially equal to its height. The sheet is provided

with a rectangular recess 11 centrally disposed along the lower edge and of a width and height adapted to receive the pedals of the piano and permit free action thereof. In order to conceal the supporting body 10, 60 produce an artistic appearance and secure the pad in place, I provide a front covering sheet 12 of fabric, leather, imitation leather, or the like. This sheet is preferably of a size substantially equal to the size of the supporting body 10 and before being applied thereto is 65 stamped by a suitable die to produce an ornamental design thereon. Preferably the stamping serves to form a wreath or other like design about the edges of the sheet and produces merely intersecting lines in the main body of the sheet serving to locate the buttons 70 employed to hold the padding in place. The marginal portions of the covering sheet are securely pasted or glued to the supporting sheet, and the central or body portion of the covering 12 is separated from the supporting sheet by a suitable padding 13. This padding 75 is first placed upon the center portion of the supporting sheet and the marginal edges of the covering are secured in place. The central or body portion of the covering is then secured to the supporting sheet by means of suitable upholstering buttons 14 located at the indicated points on the covering. These buttons serve to hold the padding 13 in place and prevent it from becoming dislocated or sliding toward the lower edge of the pad. The rear side of the pad is then covered by a layer 15 of padding material and this is secured in place 80 by a back covering sheet 16. The front covering sheet is of such a material as to present an ornamental appearance, such, for instance, as plush, satin, or the like, while the back covering sheet 16 is of such a soft material that it cannot scratch or otherwise injure the front 85 panel of the piano in contact with which the pad normally lies.

The pad is preferably held in place by clips 15^a formed of a thin strip 16^a of flexible sheet metal and inclosed within a covering 17 of leather, cloth, or the like. 95 One end of each clip is rigidly secured to the pad and the other end extends upward therefrom. The metal strip 16^a is annealed so that it may be bent to any shape desired, and in applying the pad to the piano this strip is bent to an inverted U-shape as shown in 100 Figs. 2 and 3 and serves to inclose the upper end of the front panel 18 of the instrument. The lower edge of the pad normally rests upon the floor and lateral movement is prevented by the engagement of the pad with the pedals or a part of the instrument adjacent thereto. 105

The pad forms a positive protection for all parts of the woodwork of the piano adjacent the pedals, and effectively and positively prevents the same from being injured. No separate mechanism is necessary to hold the pad in place, and thus it is evident that it may be 110 applied to any piano and after having been removed therefrom leaves no clips, fasteners or other devices

which mar the appearance of the piano and indicate that a pad has been employed.

It is evident that the ornamental border portion of the covering may be of a separate piece of material from 5 the padded body portion, if desired, or the ornamental portion may be formed with its inner edges overlapping the edges of the padded portion to hold the latter in place.

Having thus described my invention, I claim as new 10 and desire to secure by Letters Patent:

The combination of a piano protecting pad, of a height substantially equal to the front panel of the piano, and

having a recess at its lower edge adapted to receive the 15 pedals of the piano, and annealed sheet metal clips, each of the sheet and having the opposite end thereof adapted to engage with the piano adjacent the upper edge of the front panel thereof, said clips being readily bent to facilitate their use in connection with pianos of different forms.

In testimony whereof I have signed my name to this specification in the presence of two subscribing witnesses.

KATHERINE M. KEOWEN.
